CHARLES R. HADLEY COMPANY, OF LOS ANGELES, CALIFORNIA, A CORPORATION
OF CALIFORNIA.

TRAY BINDER.

Application filed May 8, 1926. Serial No. 107,563.

This invention relates to that type of loose leaf holder termed, in the art, tray binder, and an object of the invention is to provide a tray binder having a tray from 5 which the binder covers with their contents can be removed for placing in a vault, or for any other desired purpose.

Loose leaf holders employed in the art relating to accounting have heretofore been 10 of two types, the older type being simply in the form of a binder comprising covers, and a means for detachably holding the index guides and loose leaves clamped between the covers. Another type that is of 15 more recent origin is termed tray binder and comprises a tray, leaf-clamping means adjustably mounted on the tray in such manner as not to be detachable, and cover or leaf supporting members hinged to the clamping 20 means so that said covers can be opened away from each other to permit inspection of the loose leaves without the necessity of unclamping said leaves, which unclamping is only necessary when it is desired to re- 25 move or replace the loose leaves.

The present invention is distinct from both of the devices above described, in that it comprises a tray, leaf clamping means adjustably mounted on the tray, and detachable from said tray, and covers hinged to the leaf clamping means. With the old type of tray binder mentioned above, it is necessary, to safeguard the contents of the binder, to place the entire device 30 in the vault, and an advantage of the present invention over said old type of tray binder is that the tray binder may be used in exactly the same way as said old type and, furthermore, the leaf-clamping means 35 and covers, together with the leaves clamped in the binder, may be readily removed from the tray and placed in the vault. This invention also distinguishes from the old combined tray and binder, a type in which the 40 binder is set in a tray and is detachable therefrom, so that the binder can be taken out of the tray and placed in the vault. A difference that may be mentioned between the last-mentioned old type of combined 45 binder and tray therefor, and the present invention is that in said old type, the clamping means is tightened and loosened when the binder is out of the tray, whereas in 50

the present invention, the tightening and loosening may be effected while the clamping means are in the tray. 55

Another advantage of the present invention is that the cover supports are adjustable with and by the leaf-clamping means so that the binder and tray can be expanded together when it is desired to insert a greater 60 number of leaves between the covers.

Other objects and advantages will appear from the subjoined detailed description.

The accompanying drawings illustrate the 65 invention.

Figure 1 is a side elevation of a tray binder constructed in accordance with the provisions of this invention, the binder being shown in solid lines in closed position 70 and one of the covers being indicated in open position in broken lines.

Figure 2 is an end elevation of Figure 1 from the left thereof, a portion of the front 75 cover being broken away.

Figure 3 is a perspective view of the binder detached from the tray.

Figure 4 is an inverted plan view of the tray shown in Figures 1 and 2, one of the cover-supporting members being broken 80 away.

Figure 5 is an enlarged sectional view on the line indicated by 5-5, Figure 2, the leaf-clamping means being released and the front cover being in the open position as indicated 85 in dotted lines in Figure 1, the upper portions of the binder covers, its contents, and the cover-supporting arms being broken away to contract the view.

Figure 6 is a perspective view of the jaw 90 end of the crank employed in adjusting the clamping means.

Figure 7 is an enlarged fragmental view, mainly in section, from the line indicated by 7-7, Figure 1. 95

The invention comprises a binder indicated, in general, by the character 11, and a tray indicated, in general, by the character 12. The binder 11, as seen in Figure 3, may be readily detached from the tray, when 100 desired and, ordinarily, said binder when detached, will be in the closed condition.

The binder 11 is constructed as follows: There is provided a pair of leaf-clamping members 13 of L-shaped construction, the 105 longer leg of one of the clamping members

being slidably connected with the longer leg of the other clamping member, the sliding connection consisting of slots 14 in side flanges 15 of one of the clamping members 13 and studs 16 projecting from flanges 17 of the other clamping member 13, said studs engaging in the slots 14. The clamping members 13 together constitute an adjustable binder back. In this instance, the studs 16 are yieldingly mounted so that they can be retracted from the slots 14. The studs 16, in this instance, are attached to flat springs 18 secured to the flanges 17 and projecting through holes 19 in the flanges 17. The springs 18 yieldingly hold the studs in the slots and the flanges 17 form channels for the flanges 15 to slide in, thus making a telescoping connection between the clamping members 13. To separate the members, all that is necessary is to pull the springs 18 outwardly to withdraw the studs from the slots and then slide the flanges 15 out of the flanges 17.

To the clamping members 13 are secured the opposite ends of telescoping index-guide retaining members 20 which are adapted to extend through holes 21 formed in downwardly extending tabs 22 of index guides 23.

The binder back has interfitting leaf-supporting members 24, alternate ones of said members being secured to the different clamping members 13. Thus, the leaf support is of sectional construction, one of the sections interengaging the other and said sections being in slidable relation so that when the clamping members 13 are slid in and out relative to each other, the leaf support is contracted and expanded accordingly. Preferably, the members 24 are provided on their upper faces with transversely extending grooves 25 so as to insure against slippage of the guides and leaves along said members when said guides and leaves are not tightly clamped between the clamping members 13.

To force the clamping members toward and from one another, there is provided suitable means formed, in this instance, by a nut 26 and screw 27, the nut being secured in any suitable manner to one of the members 13 and the screw being rotatably supported by a bearing 28 on the other clamping member 13, said other clamping member being provided with an opening 29 through which the head of the screw projects. Said head is provided with a transversely extending pin 30, the projecting ends of which are adapted to be received in openings 31 in a shaft 32, said pins entering the openings 31 through slots 33. The shaft 32 is thus detachable from the screw and can be readily turned by a crank handle 34, so as to move the clamping members 13 toward or from one another. Hinged at 35 to the clamping members 13 are covers or leaf-supports 36.

The tray is constructed as follows: There is provided a substantially flat base 37 upon which the clamping members 13 are adapted to rest. In this instance, the base 37 is provided with feet 38, preferably rubber-covered. Projecting upwardly from one end of the base 37 are stationary cover supports 39 of angular construction so as to support one of the covers 36 at a desired angle to the vertical. Movable mounted on the base 37 is another cover support 40, also of angular construction, so as to support the other cover 36 at a desired angle to the vertical. Thus, when the covers 36 rest against the supports 39, 40, the binder is open. If the clamping members are in clamping position, as in Figure 1, with one of the covers 36 resting against the supports 39, and the other cover, as indicated in broken lines, resting against the support 40, the binder is in condition for referring to any of the loose leaves A between said covers.

The mounting for the support 40 may be constructed as follows: The lower end of the support 40 is integral with a slide 41, which is positioned beneath and in contact with the base 37. A strap 42, projecting from the under face of the base 37, extends beneath the slide 41.

Means are provided to adjustably retain the slide 41 in different positions and for this purpose is provided a detent 43, in this instance, in the form of a ball positioned in an opening 44 in the slide 41, said detent being yieldingly held toward the base 37 by spring 45, which is secured by a screw 46 to the under face of the slide 41. The detent 43 is adapted to selectively engage in recesses or notches 47 in the base 37.

The lower portion of the support 40 forms a bearing 48 for the shaft 32, said shaft extending through said bearing and being rotatably supported thereby. When the shaft 32 is turned in a direction to increase the spacing of the clamping members 13, one of said clamping members moves toward the support 40 and when it engages said support and is moved still further away from the other clamping member 13, the first-mentioned clamping member pushes the support 40 outwardly, thus simultaneously expanding the binder and the tray so as to accommodate a larger volume of loose leaves or separate the leaves that are in the binder a sufficient distance so that they can be readily removed and replaced, as is requisite in making entries on the loose leaves.

The tray is provided with adjustably mounted stops at its sides for engaging the edges of the loose leaves and said stops are indicated at 49 and are preferably in the form of flat strips extending longitudinally along the sides of the tray. The stops 49 are mounted on L-shaped standards 50, the

horizontal legs of the standards extending beneath and in sliding engagement with the base 37. Said horizontal legs slide in guides 51 secured by rivets 52 or otherwise to the 5 under face of the base 37. The stops 49 are adjustably held in different positions by a construction similar to that described above for adjustably holding the slide 41 and, the construction being the same, the elements 10 thereof will be indicated by the same reference characters with the addition of the letter "a."

The foregoing will enable those skilled in the art to make and use the invention and 15 the operation may be briefly described as follows:

Assuming at the beginning that the binder 11 is detached from the tray and that the shaft 32 is either entirely withdrawn from 20 the bearing 48 or is withdrawn so that its inner end is substantially flush with the inner end of said bearing and that it is desired to place the binder in the tray and use the same in combination therewith, the said 25 binder will be placed in the tray with the clamping members 13 resting on the base and one of the covers 36 supported by the support 39, as indicated in solid lines in Figure 7 of the drawings. If it is merely desired 30 to refer to entries on the loose leaves in the binder, the cover 36 adjacent to the support 40 will be opened against said support into the broken line position shown in Figure 1.

Now assuming that it is desired to perform 35 bookkeeping operations, either by hand or machine, on the different loose leaves, the shaft 32 will be inserted through the bearing 48 and engaged with the head of the screw 27, as shown in Figure 6, and the 40 handle 34 will be turned to open the clamping members 13, thus separating the loose leaves and relieving the pressure on their lower ends so that they may be readily extracted from the binder for the purpose of 45 making entries on said leaves. When the binder is open and the clamping members are released, the loose leaves on opposite sides of the binder are held against sliding toward one another at their lower ends by 50 the grooves 25. As new leaves are added to the binder, said binder may be expanded by turning the shaft 32 so as to further space the clamping members 13. When the binder has been expanded to the full length of the 55 space between the supports 39, 40, the shaft 32, when operated to expand the binder will cause one of the clamping members 13 to push against the support 40, thus to expand the tray in length to correspond with the expansion of the binder. The detent 43 snapping into one of the notches 47, will indicate 60 to what extent to expand the tray.

At the end of a day or at any other desired time, after it is no longer desired to 65 refer to the loose leaves, the shaft 32 will

be operated to close the clamping members together and the shaft 32 will be withdrawn from the head of the screw 27, thus freeing the binder so that it can be lifted from the tray. 70

Offsetting of the loose leaves may be accomplished in a manner well understood in this art, either or both stops 49 being slid outwardly and the leaves that are to be offset being moved edgewise until they engage 75 either one of said stops.

From the foregoing, it will be seen that there is a cooperative relation between the binder and tray and that the binder, when in 80 the tray, can be locked in place therein by the shaft 32. It is also readily seen that the binder is expanded and contracted by means mounted on the tray, namely, the shaft 32, though it is to be understood that, if desired, the shaft may be applied to the screw head when the binder 11 is detached from the tray. It is preferable, however, to operate the clamping members into open and closed 85 positions when the binder is positioned in 90 the tray.

We claim:

1. A tray binder comprising a base, clamping members slidably and loosely resting on the base, adjustable means engaging the clamping members to hold them in different spaced relations, and means on the base detachably engaging the holding means operable to adjust said holding means. 95

2. A tray binder comprising a base, clamping members slidably and loosely resting on the base, adjustable means engaging the clamping members to hold them in different spaced relations, and means detachably mounted on the base and detachably engaging the holding means operable to adjust 100 said holding means. 105

3. A tray binder comprising a base, clamping members slidably and loosely resting on the base, covers hinged to the clamping members, adjustable means engaging the clamping members to hold them in different spaced relations, supports on the base for the covers, one of said supports being movable relative to the other support and means on the base detachably engaging the holding means operable to adjust said holding means, said first mentioned support adapted to be operated into different positions by a relative movement between the clamping members. 110 115

4. A tray binder comprising a base, clamping members slidably and loosely resting on the base, covers hinged to the clamping members, adjustable means engaging the clamping members to hold them in different spaced relations, supports on the base for the covers, one of said supports being movable relative to the other support and means detachably mounted on the base and detachably engaging the holding means operable to adjust 120 said holding means, said 125 130

- first mentioned support adapted to be operated into different positions by a relative movement between the clamping members. 45
5. A tray binder comprising a tray, and an expansible binder loosely mounted in the tray, said tray and binder provided with co-operating means operable to expand the binder. 50
6. A tray binder comprising an expansible binder, and an expansible tray loosely supporting the binder and operable by expansion of the binder to expand the tray. 55
7. A tray binder comprising an expansible binder, and an expansible tray loosely supporting the binder and operable by expansion of the binder to expand the tray, said binder provided with means to expand it. 60
8. A tray binder comprising an expansible binder, and an expansible tray loosely supporting the binder and operable by expansion of the binder to expand the tray, said binder provided with means to expand it and said tray provided with an operating member engageable with the binder-expanding means. 65
9. A tray binder comprising an expansible binder provided with means to expand it, and a tray loosely supporting the binder and provided with a bearing and with a shaft to turn in said bearing, said shaft adapted to engage and operate the binder-expanding means. 70
10. A tray binder comprising an expansible binder provided with means to expand it, and a tray loosely supporting the binder and provided with a bearing and with a shaft removably supported in said bearing, said shaft adapted to engage and operate the binder-expanding means. 75
- 40 11. A tray binder comprising an expansible binder provided with means including a nut and screw to expand it, and a tray loosely supporting the binder and provided with an operating member detachably engageable with said screw. 80
12. A tray binder comprising clamping members, a base shiftably supporting the clamping members, a cover hinged to one of the clamping members, a support for said cover shiftably connected with the base, and means to move the last-mentioned clamping member into engagement with the cover support to effect shifting of said cover support to position to support the cover in the position to which it is moved by movement of the associated clamping member. 85
13. A tray binder comprising clamping members, a base shiftably supporting the clamping members, a cover hinged to one of the clamping members, a support for said cover connected with the base and provided with a bearing, means connecting the clamping members operable to relatively move said members, and a shaft rotatably supported in said bearing and engageable with said means to operate the same. 90
14. A tray binder comprising clamping members, a base shiftably supporting the clamping members, a cover hinged to one of the clamping members, a support for said cover shiftably connected with the base and provided with a bearing, means to move the last-mentioned clamping member into engagement with the cover support, and a shaft rotatably supported in said bearing and engageable with said means to operate the same to effect shifting of said cover support to position to support the cover in the position to which it is moved by movement of the associated clamping member. 95

Signed at Los Angeles, California, this 29 day of April 1926.
